GAME BOARD

Jacques Bronstein, New York, N. Y.

Application December 24, 1953, Serial No. 28,198

Term of patent 14 years

(Cl. D34—5)

To all whom it may concern:

Be it known that I, Jacques Bronstein, a citizen of the Republic of France and resident of the city of New York, Borough and county of Bronx, State of New York, have invented a new, original, and ornamental Design for Game Board, of which the following is a specification, reference being had to the accompanying drawing, forming part thereof.

The figure is a top plan view of a game board showing my new design, the game board being of conventional thickness.

I claim:

The ornamental design for a game board, as shown and described.
